UNITED STATES PATENT OFFICE.

FRANK SKLIBA, OF CLEVELAND, OHIO.

COMBINED COLLAR AND HOOD

1,117,456.

Specification of Letters Patent. **Patented Nov. 17, 1914.**

Application filed March 23, 1914. Serial No. 826,474.

To all whom it may concern:

Be it known that I, FRANK SKLIBA, a citizen of the United States, residing at Cleveland, in the county of Cuyahoga and State of Ohio, have invented a certain new and useful Improvement in Combined Collars and Hoods, of which the following is a full, clear, and exact description, reference being had to the accompanying drawings.

This invention relates to a combined collar and hood for overcoats, capes, raincoats, and other such garments; and it has for one of its objects to provide a combined collar and hood which, when folded into one position, lies smoothly over the shoulders of the garment and forms a collar of the style known as a shawl collar; and when unfolded and drawn up over the head of the wearer, forms a hood, the front of which fits snugly about the face of the wearer; and it has, for another of its objects, to provide means for fastening the front of the collar to the lapels of the garment whereby the same may be held against displacement; and to use the same means for holding the corners of the hood together underneath the chin of the wearer.

A further, and more general object is to provide a combined collar and hood of the above character which contains substantially no more material than is required for either the collar or the hood, whereby the same is rendered neat and attractive in appearance, and comfortable to the wearer.

The above objects are attained in a garment constructed in accordance with the accompanying drawing, wherein—

Figure 1 shows a garment provided with my combined collar and hood, the same being folded down over the shoulders of the garment to form a collar therefor; Fig. 2 is a rear view of the garment as shown in Fig. 1; Fig. 3 shows the hood in the act of being extended over the head of the wearer; Fig. 4 shows the hood drawn about the head of the wearer with its forward corners fastened beneath the chin; Fig. 5 is a section through the back of the neck of the garment, showing the parts folded in the position they occupy in Figs. 1 and 2; Fig. 6 is an enlarged, transverse section through the fastening means and adjacent portions of the collar and lapels of the garment, such section being indicated by the line 6—6 of Fig. 1; and Fig. 7 shows an underneath view of

the combined collar and hood detached from the garment.

In the drawing, the garment 1 is shown as provided with the usual lapels 2, and attached to the neck of the garment is a U-shaped piece of material 3 which has a neck opening 4 that corresponds in shape to the neck of the garment, such piece 3 being stitched to the neck of the garment about the opening 4. The inner edge of the piece 3 extends about the neck of the garment from the upper end of one of the lapels to the upper end of the other.

A member 5, which corresponds in material and substantially in shape, to the piece 3, is superimposed on the piece 3 and has its outer edge attached to the outer edge of said piece, and the member 5 is provided with a neck opening 6. The inner edge of this member is of greater length than the corresponding edge of the piece 3, so that, when it is in the position shown in Figs. 1 and 2, it projects down over the diagonally cut ends 7 of the piece 3 and overlies the lapels 2.

The free corners of the member 5 are held to the lapels by any suitable means, preferably by fastening devices which are known as glove buttons or fasteners, and one of the corners of the member 5 carries the part of the glove fastener which contains a socket 8 and which is shown at 8, while the other corner carries the part 9 which is provided with a knob. Carried by one of the lapels 2, is that part 9^a of a fastener which is provided with a socket for the reception of the member 9, and the other lapel is provided with that part 8^a of a fastener which cooperates with the member 8. This arrangement enables the same fastening means which are used for holding the parts in place when in position as a collar, to be used for holding the corners of the hood together beneath the chin of the wearer, when the hood is drawn over the head.

It will be seen from the foregoing description that when the device is used as a collar, the piece 3 and the member 5 lie closely together as shown in Fig. 5, and fit smoothly over the shoulders and about the neck of the garment. It will be observed, also, that the rear portions of the piece 3 and the member 5 contain sufficient material to allow them to be extended up over the head of the wearer and to project to the front of the head, and that the opening 6 of the member

5 is of a proper size to fit snugly about the face of the wearer, in which position it is held by the cooperation of the fasteners 8 and 9.

5 Having thus described my invention, what I claim is:—

10 1. A combined collar and hood for garments of the character set forth, comprising a member which has an opening that corresponds in shape to the neck of the garment, the member being attached to the neck of the garment about said opening, and a second member corresponding substantially in size and shape to the former member and which has its outer edge attached to the outer edge of the first mentioned member.

15 2. A combined collar and hood for garments of the character described, which comprises a member having an opening that corresponds in shape to the neck of the garment, the member being attached to the neck of the garment about said opening, a second member which corresponds in size and shape to the first member and which overlies the same and has its outer edge attached to the corresponding edge of the first mentioned member, and means for detachably securing the forward corners of the last mentioned member to a portion of the 20 garment.

25 3. A combined collar and hood for garments of the character set forth, which comprises a member having an opening that corresponds in size and shape to the neck of the garment, which member is attached thereto about said opening, a second member which corresponds substantially in size and shape to the first mentioned member and superimposed on the same, having its outer edge attached to the corresponding edge of the first mentioned member, the forward ends of the last mentioned member being secured to the forward ends of the neck of the garment, and a means for 30 securing the forward ends of the last mentioned member to the lapels of the garment.

35 4. A combined collar and hood for gar-

ments of the character set forth, which comprises a member having an opening that corresponds in size and shape to the neck of the garment and which member is attached thereto about said opening, a second member which corresponds substantially in size and shape to the first mentioned member and superimposed on the same and having its outer edge attached to the corresponding edge of the first mentioned member, the forward ends of the last mentioned member projecting forward beyond the front ends of the last mentioned member and overlying the lapels of the garment, and a fastening device for attaching each of the forward ends of the second member to the adjacent lapel of the garment, one of the devices 40 carried by said member consisting of a part having a knob, and the other, consisting of a member having a socket for the reception of said knob.

45 5. A combined collar and hood for garments of the character set forth, which comprises a member having an opening that corresponds in size and shape to the neck of the garment and which member is attached thereto about said opening, a second member 50 which corresponds substantially in size and shape to the first mentioned member and which is superimposed on the same and having its outer edge attached to the corresponding edge of the first mentioned member, the forward ends of the last mentioned member projecting forward beyond the front ends of the first mentioned member, and a fastening device for attaching each of the forward ends of the second member 55 to the adjacent portion of the garment, one of the devices carried by said member consisting of a part having a knob, and the other, a part having a socket for the reception of said knob.

60 In testimony whereof, I hereunto affix my signature in the presence of two witnesses.

FRANK SKLIBA.
